UNITED STATES PATENT OFFICE.

GEORGE L. REICHHHELM, OF NEW HAVEN, CONNECTICUT.

GASIFIER AND FIXING DEVICE.

1,310,927.

Specification of Letters Patent. Patented July 22, 1919.

Application filed July 7, 1917. Serial No. 179,154.

To all whom it may concern:

Be it known that I, GEORGE L. REICHHHELM, a citizen of the United States, and resident of New Haven, in the county of New Haven 5 and State of Connecticut, have invented certain new and useful Improvements in Gasifier and Fixing Devices, of which the following is a specification.

This invention relates to a device for gasifying and fixing fluids, such as fluid fuel including volatile oils.

One of the objects of the invention is to facilitate mixing of liquid fuels and fixing the same.

Another object is to control the relative proportions of air and liquid fuel forming constituent parts of the mixture.

Another object is to provide a simple and compact arrangement including a gasifier, fixing means, burner, and an associated device in which gases formed by the gasifier and fixing means will be consumed.

Another object of the invention is to provide a gasifier, a fixer and burner combination adapted to meet the various requirements for successful commercial operation.

These and other objects are accomplished by providing the combination of heat emitting means, means for supplying oil in the 30 form of a foam, means for supplying air to mix with the oil foam and projecting the mixture against the heat emitting means for fixing the mixture, and means associated therewith in which the resultant gas may 35 be consumed.

The invention is illustrated on the accompanying sheets of drawings, in which,

Figure 1 is a side elevation of my gasifier fixing and burner combination;

Fig. 2 is a fragmentary plan view of the same;

Fig. 3 is a fragmentary plan view of a modified arrangement in which a steam injector is used;

Fig. 4 shows more in detail a complete arrangement in which a steam injector is used;

Fig. 5 is a detail sectional view taken in the plane of line 5—5 of Fig. 4, and,

Fig. 6 is a fragmentary side elevation of a further modification of my invention.

The various novel features of the invention will be apparent from the following description and drawings and will be particularly pointed out in the appended claims.

In this application I am concerned primarily with the proper supply of oil in the

form of a foam, the oil foam being taken up or mixed with air and the resultant mixture projected against a heated surface for fixing the gas, and means for heating the heated surface and consuming the gas formed.

Referring first to Figs. 1 and 2, it will be noted that I have provided an air inlet pipe 10, the supply of air thereto being controlled by a valve 11. The air is preferably supplied under pressure by a fan 12. Air, after passing the valve 11, divides proportionately in accordance with the angular position of a 60 throttle valve 13 and passes through two pipes 14 and 15, the latter of which extends downwardly and has a horizontally arranged portion 16 which extends into an oil receptacle 17 supplied with oil from a tank 18 by a suitably driven pump 19 through a pipe 20. The oil in the receptacle 17 is maintained at a constant level, the excess amount passing through an overflow connection 21 leading back to the supply tank 80 18. The laterally extending portion 16 of the pipe 15 is provided with a series of openings 22, which openings are located below the level of the oil in the receptacle 17. Air passing through the pipe 15 causes oil in the 85 receptacle 17 to bubble up through an outlet nozzle 23 in the form of a foam. This nozzle 23 extends into the pipe 14 and as a result thereof oil foam issuing from the nozzle is picked up, atomized and mixed 90 with air which is supplied through the pipe 14, the resultant mixture passing through an irregular zigzag pipe 24 and first splayed against an inclined surface 25. The mixture then passes down over an oppositely inclined 95 surface 26, and then successively strikes surfaces 27, 28 and 29 after passing down intermediate surfaces 30 and 31. All of these surfaces are heated by gas flames issuing from openings 32 formed in the upper side 100 of a burner 33. The burner receives the gas from the zigzag pipe 24 through a passageway 34. As a result of the fuel being supplied in the form of a foam, very fine particles of liquid fuel are picked up and 105 carried away from the nozzle 23, the action being substantially the same as that of an atomizer. The stream of fluid passing from the pipe 14 into the zigzag pipe 24 is a mixture of oil globules and air, and as stated above, the stream is splayed against the heated surface 25, then passes on and strikes surfaces 27, 28 and 29 in turn. Flames which impinge the lower surface of the zig-

zag pipe 24 heat it to a considerable degree. Any vapor which is formed in the pipe 24 will pass down over the surfaces 26, 30 and 31 having a wiping effect, and will then be 5 progressively projected against the surfaces 27, 28 and 29. If there should be any globules of oil which are not vaporized upon being splayed against the first heated surface 25, they will be forced against the next surface, etc., until arriving at the last heated 10 face, etc., until arriving at the last heated surface when the gas will be positively fixed.

Oil may be projected against a hot surface, and so long as the oil is not heated to 15 too high a temperature there will be no sign of cracking, but if the oil is left in a stationary position and heat imparted to it to a sufficient degree a deposit of carbon will be the result. Oil has been splayed against these heated surfaces in question and it is 20 found that so long as these surfaces are maintained at a temperature above the vaporizing point of the oil no trouble whatsoever is encountered in preventing what is called cracking. The surfaces can be kept 25 at a comparatively high temperature, that is, above a red heat without causing any cracking. This is attributed to the fact that oil surrounded by air will not become heated to a temperature high enough to crack it. 30 The resultant vapor upon being projected against another hot surface causes the gas to become a degree nearer fixation. Of course it is apparent that if large volumes of gas are being treated the number of heating steps should be increased. 35

Instead of supplying air under pressure by a fan, as shown in Fig. 1, air can be drawn into the pipe 35 (see Figs. 3 and 4) by high velocity steam passing into the pipe 40 35 from an injector 36. The balance of the action would be quite the same as when the fan or blower is used except that the steam remains an inert gas; however, in some cases it is desirable to use steam in place of installing a blower. By the action of air through the pipe 37 and openings 38 in the laterally extending part thereof, oil in the form of foam is projected from the oil receptacle 39 through the outlet tube or nozzle 40 having a plurality of relatively small outlet openings 41. When steam is forced through the injector it will cause the induction of air into pipe 35 and in order to make the heating surfaces 42 and 43 as small as 50 possible only enough steam and air is taken through the passageway 35 to make a fixed gas which will be discharged through a nozzle 44 and at this point induct the balance of the necessary air into the burner 45 for 55 combustion purposes. In this way a smaller volume of fluid is passed through the vaporizer and gasifier because if the gas is fixed before arriving at the nozzle 44 the action from that point will be the same as in an 60 ordinary cook stove burner. 65

As shown in Fig. 6 I have provided an alternative plan in which a separate pipe 46 is led directly to the oil receptacle. It has been found by actual experiment that the velocity of air passing the nozzle 48 is sufficiently great to exert pulling power upon this nozzle and by installing a pipe 46 and a valve 49 to take the place of the connection 37 shown in Fig. 4, an oil foam will be formed at the nozzle 48 to meet the requirements. 70 75

In the arrangement disclosed in Figs. 4 and 6 I have also provided a glass tube 50, which is for the purpose of collecting water in case any condensation from the steam 80 should flow into the oil receptacles 39 and 47. This condensation would seek the lowest level and when water has accumulated to a given level 51, for example, the pet cock 52 may be opened for draining off the water. 85

Among other applications of my invention it may find particular value in connection with locomotives. In Fig. 2 I have shown a suitable heat supply source 60 adjacent the burner 33. Where steam is used 90 the heating surfaces 42 and 43 may be heated preliminarily by passing steam over said surfaces, steam at 180 lbs. pressure being capable of heating the surfaces to at least 350 degrees Fahrenheit. Under such conditions it is possible to start the burner 45 (see Fig. 4) on some of the relatively heavy fuels, such for example, as kerosene oil, the vaporizing point of which is far below the 95 temperature mentioned. 100

Where fuel is supplied in the form of bubbles or foam it is possible to maintain a constant mixture, that is, the higher the rate of flow of air the greater will be the number of bubbles projected up through the nozzle. 105 It will be noted that the level of the oil in the oil containing receptacles 17, 39 and 47 is automatically maintained constant and this level is sufficiently low to make it impossible for oil to run into the vaporizer or burner thereby making the arrangement 110 relatively safe.

It is apparent that there may be various modifications of the invention herein particularly shown and described, and it is my 115 intention to cover all such modifications which do not involve a departure from the spirit and scope of the invention as set forth in the following claims.

I claim:

1. In a device of the class described, the combination of means having a hot surface, means for supplying air and hydro-carbon in the form of a foam, and means for projecting the mixture against the hot surface 125 for fixing the resultant gas.
2. In a device of the class described, the combination of heated means, means for supplying air and hydro-carbon in the form of a foam, and means for supplying air to 130

- carry the foam into engagement with said heated means to fix the resulting gas.
3. In a device of the class described, the combination of means for supplying air and hydro-carbon in the form of a foam, and means for supplying air to said foam to produce a combustible mixture.
4. In a device of the class described, an oil reservoir having a supply outlet, and a fluid connection to said oil reservoir having an opening therein below the level of the oil whereby oil in the form of a foam may be supplied to the outlet of said receptacle.
5. In a device of the class described, an oil reservoir having a supply outlet, a fluid connection to said oil reservoir having an opening therein below the level of the oil whereby oil in the form of a foam may be supplied to the outlet of said reservoir, and means whereby a fluid may be passed by said outlet portion to mix with the oil foam.
6. In a device of the class described, the combination of means having a plurality of successively arranged hot surfaces, means for supplying oil in the form of a foam, and means for supplying air to carry said oil as a mixture successively against the hot surfaces of said means.
7. In a device of the class described, the combination of a passageway terminating in a step portion, means for heating said step portion, means for supplying fuel to said passageway in the form of a foam, and means for supplying air through said passageway to project the resulting mixture against said hot step portion.
8. In a device of the class described, the combination of a passageway terminating in a zigzag portion to form a plurality of steps, means for heating said zigzag portion, means for supplying air and oil in the form of a foam to said passageway, and means for carrying the foam over the heated steps.
9. In a device of the class described, the combination of a passageway, a heater in open communication therewith and arranged to heat said passageway, means for supplying air and fuel to said passageway in the form of a foam, and means for supplying air to said passageway whereby the resulting mixture may be fixed.
10. In a device of the class described, the combination of a passageway having a stepped portion, a heater in open communication with said stepped portion arranged to heat the said stepped portion, means for supplying oil to said passageway in the form of a foam, and means for supplying air to said passageway whereby the resulting mixture may pass through the stepped portion, be fixed therein and passed into said heater.
11. In a device of the class described, the combination of a passageway, an oil containing receptacle having an outlet nozzle connected to said passageway, a fluid conveying pipe extending between said passageway and said oil receptacle and having an opening in said receptacle below the level of the oil therein whereby fluid may pass from said passageway into said oil containing receptacle to supply oil in the form of a foam at said nozzle.
12. In a device of the class described, the combination of a passageway, an oil containing receptacle having an outlet nozzle connected to said passageway, a fluid conveying pipe extending between said passageway and said oil receptacle and having an opening in said receptacle below the level of the oil therein whereby fluid may pass from said passageway into said oil containing receptacle to supply oil in the form of a foam at said nozzle, and means for controlling the quantity of foam supplied to said passageway.
13. In a device of the class described, the combination of a passageway, an oil containing receptacle having an outlet nozzle connected with said passageway, a fluid conveying connection between said passageway and oil containing receptacle having an opening within said receptacle below the level of the oil therein whereby oil in the form of a foam may be supplied to said passageway, and a valve in said passageway to control the relative quantities of fluid supplied to said oil receptacle and passed said nozzle.
14. In a device of the class described, the combination of an air passageway, an oil containing receptacle below the same having an outlet nozzle extending upwardly into said passageway, and means for supplying air through said passageway and to said oil containing receptacle to raise oil up into said passageway in the form of a foam.
15. In a device of the class described, the combination of a burner, a passageway leading to said burner, means for supplying oil to said passageway in the form of a foam, and means for conveying air through said passageway to produce a combustible mixture which becomes fixed in said passageway and part of which is supplied to said burner to heat said passageway and the remaining part being supplied for another heating purpose.

Signed at New Haven, Connecticut, this 2nd day of July, 1917.

GEORGE L. REICHELIM.
